DRAWER FOR FILING CABINETS

André Antoine Chauvin, Paris, France; vested in
the Attorney General of the United StatesApplication April 2, 1947, Serial No. 739,013
In France September 27, 1941Section 1, Public Law 690, August 8, 1946
Patent expires September 27, 1961

3 Claims. (Cl. 45—2)

1

The invention particularly relates to filing cabinets with so-called, continuous, visible and vertically hung filing, comprising envelope-files hung from supporting rods, which can be moved on the fixed slideways of a frame or framework. Reference will more especially be made to the filing cabinets of the type having formed the subject-matter of the French Patent No. 804,724, dated July 26, 1935, and essentially characterised by the fact that in order to form by means of the envelope-files a kind of uninterrupted accordian, the latter are coupled two by two by means of supporting rods.

If the advantages of such a system have been recognized by use, the fact still remains that it is of excessive cumbersomeness because, in order to consult the files, it is necessary to provide a certain clearance between them and, consequently, to take care not to charge the filing cabinet so that the supporting rods fill up all the available space of the slideways.

The object of the present invention is to remedy this serious inconvenience and consequently to very appreciably increase the capacity of the filing cabinet without prejudice to the facility of consulting and classifying the files. For that purpose, the front face of each drawer must be rendered movable so that when pulling forwardly the handle or other member with which it is provided, it draws along the movable slideways arranged to extend the fixed slideways of the frame, thus imparting, on the one hand, to the supporting rods which completely fill up the latter, the possibility of acquiring the clearance necessary for their manipulation and, on the other hand, to the file-carrying envelopes, the facility of being opened in order to allow, either the desired file to be consulted, or the removal of documents or introduction of new documents. The same result can be obtained by rendering the usual slideways or their attaching means extensible, so as to follow the movements of the handle.

Another object of the invention consists in combining with said handle or the front face, a device automatically locking the front part rendered movable according to the invention so as to prevent any removal of documents when the drawer, pushed home in its housing, is, in the usual manner, locked at the rear by means of the known lock and rack closing device.

The accompanying drawing given by way of example shows, among others, some embodiments of the invention.

Fig. 1 is a diagrammatic view of a filing cabi-

2

net with vertically hung files showing the space compulsorily sacrificed on the slideways *a* in order to have, at every instant, the necessary clearance, for instance at *b*, of the supporting rods for the rational utilisation of the filing cabinet.

Fig. 2 also diagrammatically shows the purpose contemplated by the invention and which allows of completely filling up the slideways with the rods which serve for hanging the envelope-files whilst doing away with the lost space *b*.

Fig. 3 illustrates a first embodiment according to which the front face *c* of the drawer *d* is removable and draws along with it, by actuating the handle *e*, lateral cheek members *f* the upper edge *f*¹ of which forms an extension of the edge *d*¹ of the cheek members forming slideways of the drawer proper, and on which the supporting rods can be caused to slide until the desired file has been disengaged. Thus, every facility will be had, for obtaining, owing to the extension of the slideways, the space *b* of Fig. 1, necessary for the free action of the rods and the entire capacity *a* of the filing cabinet will finally have been completely used. It will be readily understood that a stop, for instance a small stud *g* can abut against the edge of the fixed drawer proper *d* and limit the stroke of the movable extension *f*.

Fig. 4 clearly shows how the use of supplementary slideways, exactly in alignment with the usual slideways, allows the spacing apart of the supporting rods giving access at *b* to the envelope-file to be consulted, although said supporting rods, as shown in Fig. 2, completely fill up the normal slideways in position of rest.

Instead of moving normally according to a horizontal direction, the extension *f* could simply pivot at *h* on the front base of the drawer, the lateral cheeks being then cut out in the form of semi-circular sectors as seen in Fig. 5, on the edge *f*¹ of which the supporting rods could engage as easily as in the embodiment according to Fig. 3.

The extension of the slideways could be obtained owing to the extensibility of the material employed. For instance, the latter might be constituted by a coil spring *r* (see Fig. 6) having very close turns and capable of extending along the necessary length *b* to follow the forward pulling or rocking of the movable front face *c* of the drawer *d*, said displacements being preferably guided by a compass *i*. In order to avoid any yielding of the slideway under the weight of the files, the spring *r* on which the supporting rods *t* (see Fig. 7) are placed by means of their

usual notches, could rest in a groove provided at the upper part of the lateral cheeks of the drawer or on a sheet metal plate which would be secured thereon.

The slideways might also, as shown in Fig. 8, be constituted by a flexible wire *k* guided by rollers *l l'* and restored by a coil spring *m*.

Finally, Figs. 9 and 10 show, in two successive opening positions, a modification according to which the movable slideways are obtained by rods *n* broken in the form of compasses.

The opening of the front part of the drawer, a certain number of embodiments of which have been given above by way of examples and not in a limiting sense, shows that the usual closing of said drawer with locking at the rear by means of lock and rack becomes insufficient, since said drawer remains accessible by the fact that the front is rendered movable. It is therefore necessary to provide another system for locking said movable part when the handle has pushed the drawer back home, that is to say in the position in which the rear locking can take place in the usual manner. The present invention has solved this problem by arranging a front locking link-work actuated by the opening or closing movements imparted to the handle of the drawer.

Figs. 11 to 14 show in perspective views an embodiment of this device applied to a drawer *d* having a rocking front face *c*. In the fixed slideway *d'* slide telescopic slideways *f'* which the forward movement of the handle *e* causes to come out exactly in alignment with the fixed slideways on which the supporting rods *t* are arranged. For that purpose, the movable slideways *f'* are united by a bar *f²* which is rendered rigid with the front face *c* by resilient fingers *f³*. The slideways *f'* might also be actuated by hand, by acting on the bar *f²*. On the front face *c* of the drawer are secured bell-crank link-works *v, x, y* pivoting at *z* on the lateral wall of the drawer, Fig. 11 showing the open position and Fig. 12 the closed position according to which the finger *y*, lowered, can engage in a stop *y²* secured on the differential slideway *y³* for the forward movement of the drawer. On the contrary, in open position, the bar *x* abuts against a stop *s* secured on the lateral wall of the drawer.

The rods *v* guided in notches *o* of said wall, can not only be rigid with the front face, but can form extensions of the lateral branches of the operating handle *e*.

Figs. 13 and 14 clearly show how the passage of the supporting rods *t* of the fixed slideway on the movable slideway and reversely takes place without shocks, for opening the pocket *p* or the retracting of the rods at the front in order to reach any pocket among those distributed all

along the slideways *d'*. For that purpose the junction between the slideways *d'* and *f'* is preferably effected by means of an incline *q* over the edges of which the notches of the rods *t* progressively straddle.

I claim:

1. A drawer for filing cabinet of the type having vertically hung files, said drawer having a bottom, two sides, a movable front connected for horizontal swinging movement relative to the bottom, fixed file-supporting slideways along the upper edges of the sides, movable file-supporting slideways operatively connected with the inner face of the movable front and slidably telescoped within the fixed slideway to form extensions of the latter on the forward swinging of the movable front, a cross bar in said drawer connecting the front edges of said movable slideways and resilient fingers carried by the inner surface of the movable front near the upper edges thereof for operative connection with said cross bar.
2. A drawer for filing cabinet as claimed in claim 1 in which differential drawer supporting slideways are also associated with the outer surfaces of the side walls of the drawer near the bottom thereof, slotted stops secured on each of the differential slideways, bell-crank levers also fulcrumed on the outer surface of the side walls of the drawer the outer portions of which are adapted for engagement with the slotted stops when the drawer is closed, link members operably mounted through the movable front of the drawer and pivotally connected to the inner portions of the bell crank levers and stops fixed on the side walls of the drawer and against which the inner portions of the bell crank levers bear when in open position to limit outward movement of the link members.
3. A drawer for filing cabinet as claimed in claim 2 in which the link members are slidably arranged through the front of the drawer and a cross bar serving as a handle positioned exteriorly of the front of the drawer for connecting the forward ends of the link members together.
